CLAIM

I claim the ornamental design for the vest, as shown and described.

DESCRIPTION

FIG. 1 is a perspective view of a vest showing my new design;

FIG. 2 is a front side elevational view thereof;

FIG. 3 is a top view thereof;

FIG. 4 is a right side elevational view thereof;

FIG. 5 is a left side elevational view thereof;

FIG. 6 is a back side elevational view thereof; and,

FIG. 7 is a bottom view thereof.

The broken lines in the drawings depict stitching and represent part of the claimed design.

1 Claim, 4 Drawing Sheets
